MACHINE FOR TREATING LABELS AND APPLYING THE SAME TO CANS.

1,135,295.

Specification of Letters Patent. Patented Apr. 13, 1915.

Original application filed November 4, 1910, Serial No. 590,747. Divided and this application filed November 8, 1912. Serial No. 730,297.

To all whom it may concern:

Be it known that I, FREDERICK H. KNAPP, citizen of the United States, residing at Westminster, in the county of Carroll and State of Maryland, have invented certain new and useful Improvements in Machines for Treating Labels and Applying the Same to Cans, of which the following is a specification, reference being had therein to the accompanying drawing.

This invention relates to an apparatus for treating labels and applying the same to cans and the like, the present application being a division of my pending application for Letters Patent filed Nov. 4, 1910, Serial No. 590,747 entitled "Method of and machine for treating labels and applying same to cans."

It is common in the can labeling machine art to apply a coating of paste to the can body, which latter is moved into contact with the label whereby the latter is applied to the can, and it is also common to apply the label to the can by moving the latter over a previously pasted label, but in either case objections have arisen primarily because of the fact that the label has been applied and affixed to the can immediately or shortly after the pasting operation, and before the label has had an opportunity to become properly tempered after the moistening effect of the paste. It is well known that the labels, after becoming moistened or wet by the pasting, stretch and expand to a considerable degree, and as ordinarily applied this stretching takes places subsequently to the application of the label snugly and tightly about the can. The labels when thus applied to the can without previously being given a chance to swell, stretch or expand, after becoming dry on the can present an unseemly appearance due to wrinkling, and it often happens that the labels even become loose and at points separated from adhering contact with the cans.

The primary object of the present invention may be said to reside in a novel, economical and efficient machine adapted in its operation to so temper the label, or to permit the same to become stretched and expanded after being moistened by the paste, and prior to its application to the can, with the obvious result that when applied the expansion of the label has occurred and the

reactionary contraction will take place subsequently to its application to the can, so that the label when completely contracted about the can will be found to have a snug and smooth fit about the can and will be free from the customary wrinkles.

It is appreciated that the invention is susceptible of a large variety of embodiments and the accompanying drawings show one of the preferred embodiments which has proven satisfactory to a high degree, and will serve to illustrate the principles involved in the invention though it is not to be presumed that the same is to be limited to this particular embodiment.

More particularly the machine comprises a series of carriers which, in the instance illustrated, take the form of mandrels connected one to the other, and which are adapted to contact with a body of paste to receive a coating therefrom and subsequently pick up a label, the latter being wound about the mandrels and thereby receiving its proper curve and coating of paste therefrom, though it is obvious in this connection that the label may be first pasted through other instrumentalities, and subsequently taken up by the mandrels. When applied to the mandrels, the labels are carried to the point of application to the cans, which latter may be fed either by hand or automatic means, the former being illustrated in the drawing. During the travel of the carrier or mandrel from the point of pasting to the point of application of the labels mounted thereon to the cans, the pasting and can labeling mechanism being considerably removed one from the other, the label will have become first stretched, so that when applied to the can the subsequent contraction will cause it to snugly and firmly fit about the can, and when dried the same will be found to be devoid of wrinkles.

Though not essential, it is preferred, as above suggested, to form the mandrel or carrier of a curvature somewhat corresponding to the curve of the cans whereby a slight preliminary curve is given to the labels, and the latter will consequently readily conform to the curve of the can in the application of the latter. In this connection, however, it is not desired to limit the application of the invention to curved cans, or in fact to any particular kind of cans, and it is to be borne

in mind that wherein the term "can" is employed herein, this term is understood to include boxes and packages regardless of shape or character.

5 It is also contemplated by the invention to make it possible to give to the mandrel or carriers an uninterrupted feed whereby succeeding mandrels may be brought automatically into operative position relative to 10 succeeding cans to be labeled as the cans are placed in labeling position, with the result that the labeling of the cans may be continuous, as is the case where the labels are pasted and immediately applied to the cans, 15 as in the usual practice. Hence it follows that no delay is occasioned by the preliminary tempering of the labels.

Other improvements and the various 20 novel details in the construction and arrangement of the parts of the machine will be pointed out in the following detailed description which for a clear understanding of the invention should be read in connection with the accompanying drawings 25 wherein, as previously stated, is disclosed for the purpose of illustration, a preferred embodiment of a machine for carrying out the method stated.

Figure 1 is a side elevation of the 30 machine, Fig. 2 is an enlarged side elevation of the forward end of the machine, Fig. 3 is a front end elevation enlarged of the same, Figs. 4, 5, 6 and 7 are enlarged detailed views of the label carrying mandrel.

35 With more particular reference to the drawings, a suitable platform or flooring 1 is provided, which constitutes a main support for the various parts of the machine. Projecting upwardly from the support 1 40 adjacent what may be called the front end thereof is a pair of separated overhanging bracket arms 2, while somewhat similar bracket arms 3 are mounted adjacent the opposite end of the support. The bracket 45 arms 3 constitute separated supports for a transversely extending shaft 4, which latter is mounted in suitable bearings 3^a at the upper end of the bracket members 3. Secured to the support for the shaft 4 in any 50 desired manner is a vertically extending rod 5, secured at its upper end in any convenient manner to the transversely extending shaft 6. The bracket arms 2 also have secured thereto and constitute separated supports 55 for a transversely extending shaft 7 conveniently mounted in bearings 2^a at the upper end of said bracket arms 2. Projecting between the shafts 6 and 7 and secured to each in any desired manner is a vertically 60 inclined connecting rod 8, an additional support 9 for said shaft 2 and rod 8 being suitably mounted on the support 1 as shown. Adjacent opposite ends of each of the shafts 4 and 6 are drive wheels conveniently taking 65 the form of sprocket wheels 9^a and 10 re-

spectively, while positioned upon the shaft 7 are relatively enlarged sprocket wheels 11, each of said sprocket wheels 9^a, 10 and 11 being freely rotatable on their respective shafts. Projecting between and mounted 70 upon the said sprocket wheels are endless drive members shown as sprocket chains 12 and extending between the respective chains and secured thereto in any desired manner are supporting rods or shafts 13' upon each of which is loosely sleeved for rotation, a carrying member or mandrel 14 which in the instance illustrated are round in cross section and hollow, and the diameter thereof 75 preferably being larger than the diameter of the cans to which the label is to be applied. Means are provided for normally positioning a predetermined portion of the periphery of the mandrels lowermost, the same being shown for illustration in the 80 form of weights 14^a secured to the inner surface of the mandrels and extending longitudinally thereof, and in order to prevent lateral vibration of the mandrels during the travel of the chains, a suitable latch 15 is 85 provided, the same preferably comprising an elongated spring arm secured to the shaft 13, or the connected link of the chain as shown and adapted at its free end to automatically engage in a notch or recess 16 90 formed in the end of the mandrel 14 as the weight within the mandrel brings the latter into proper position. The recess 16 is relatively slight, so that the rotating action of the spring arm may be readily overcome, to 95 permit of the free rotation of the mandrel in the operation of the apparatus to be more particularly referred to hereinafter. Also in the periphery of the mandrels is arranged a finger opening 17 conveniently midway of 100 the ends of the mandrel and to one side of the weight 14^a in the latter, the purpose of 105 which opening being to permit of the insertion of the fingers of the operator so as to grasp the edge of the label mounted on 110 the mandrel, it being noted in this connection, as above mentioned, that the mandrel has a diameter in excess of that of the cans to be labeled, whereby, when applied to the 115 mandrels in a manner to be described, one end of the label will overlie a portion only of the opening 17 in the mandrel, thereby leaving an exposed edge or end of the label which as before explained may be readily 120 grasped by the fingers of the operator, or other mechanical means which may be employed to strip the label from the mandrel and apply the same to the cans.

Positioned upon the support 1 in any desired manner is a receptacle 18 adapted to 125 contain paste or other suitable adhesive, and mounted within the receptacle is a carrier or paste applying member, conveniently a roller 19, and preferably having a yieldable tread as of felt 20. The periphery of the 130

roller projects above the open top of the receptacle 18 and into the path of the mandrels. To one side of the paste receptacle 18 and conveniently resting on the support 1 is a receptacle 21 adapted to contain a series of superimposed labels 22, the said receptacle being preferably provided with a follower of any of the approved types commonly employed in the can labeling machine art for automatically feeding the labels in the receptacle whereby to position the uppermost one adjacent the open top of the receptacle, and it is not deemed necessary to show such a follower in the present case. The sides and forward end of the label receptacle may be cut away at 23, so as to expose an end of the uppermost label, whereby it may be readily taken up by a mandrel as it is moved past the same by the carrying chains 12 previously described.

Also positioned upon the support 1, adjacent the rear end of the label receptacle is what may be termed a label ironing or presser member, the same preferably comprising a block or support 24 upon which is mounted a yieldable pad 25 of any desired material, suitably felt, the purpose of which being to engage the labels which have been applied to the carrier or mandrel, as the mandrels move past the ironing member 24, so as to smooth the label about the mandrel and to insure the contact of the label with the pasted area of the mandrel whereby the label will receive its supply of paste from the mandrel.

Preferably a common operating means is employed for the paste applying member 19 and the mandrel carrying chains 12, the same comprising a drive shaft 26 suitably supported in any desired manner as by hanger brackets projecting downwardly from the flooring 1, said shaft adapted to be driven from any suitable source of power, as by a belt 28, engaging a pulley 29 fixed to the shaft 26. Secured to the shaft 26 for movement therewith is a sprocket wheel 30 and also a gear pinion 31. A chain 32 mounted upon the sprocket wheel 30 is arranged to engage a sprocket wheel 33 secured to the shaft 34 of the paste applying member 19, the wheel 33 being arranged without the receptacle 18, as shown. A vertically extending rotatable shaft 35 having adjacent one end a worm 36 and adjacent its opposite end a bevel pinion 37 is mounted in suitable bearing sleeves 26^a, the same sleeves being respectively on one of the bracket arms 3 and the support 1. The bevel gear 37 is adapted to mesh with the bevel gear 31 on the shaft 26, while the worm 36 is arranged to mesh with a worm gear 38 having a fixed connection with one of the sprocket wheels 9^a, which latter has a fixed connection with its

companion sprocket wheel 9^a as by a connecting sleeve 39 loosely mounted on the shaft 4. In this way, the sprocket wheels 9^a are driven by the drive shaft 26 to impart rotary movement to the chains 12 and the connected mandrels, and likewise the paste applying member 19 is driven from said shaft 26 by the chain 32, but it is noted in this connection that the movement of the chains and their connected mandrels is much slower than that of the paste applying member, this for the reason that it is desired to give the labels which are applied to the pasted mandrels ample time to receive the paste therefrom and become stretched and expanded during the travel of the chains 12 to the discharge end of the chain travel. The relatively slow movement of the mandrel carrying chains is also of importance when the rotary paste feed 19 is employed, whereby as the mandrels contact with the paste feed the rapid rotation of the latter will apply a coating of paste entirely around the mandrels, as the carrying chains slowly move past said pasting member.

From reference to Fig. 1 it will be seen that the upper surface of the presser pad member, the label receptacle and the periphery of the paste applying roller 19 are in substantially the same horizontal plane, and also that the bottom of the sprocket wheels 4 and 11 are in substantially the same horizontal plane whereby to space the chain carriers 12 a sufficient distance above the paste applying member 19, label receptacle 21 and presser pad 24 to permit the mandrels in the travel of the chains to contact with said parts.

The operation of the parts thus far described may be set forth as follows: It being assumed that paste has been placed within the receptacle 18, and that a supply of labels has been positioned face downward in the receptacle 21, traveling movement of the chains 12 about the sprocket wheels is effected through the sprocket wheels 9^a which as previously described have gear connection with the drive shaft 26. Likewise rotary movement is imparted to the paste applying member 19 by the drive shaft 26 through the chain 32. The weights 14^a within the mandrels bring a predetermined portion of the periphery of the latter lowermost, while the opening 17 in the mandrel will be slightly to the right side of the mandrel as the latter move into contact with the paste applying member 19. As soon as the mandrel engages the paste applying member, the relatively light spring arm or latch 15 is automatically released from the recess 16 at the end of the mandrel, the mandrel will be rotated about the periphery of the paste roller 19 by the latter, and receive a coating of paste. Upon

being released from the paste applying member 19 by the continuing movement of the chains 12, the mandrel will be moved by the weight therein into proper position to engage the exposed end of the uppermost label in the receptacle 21, which label will be taken up by the mandrel during the traveling movement of the latter over the upper edge of the receptacle which latter constitutes a runway and as soon as the same engages the mandrel will release the spring arm 15 as previously thereby permitting the mandrel to rotate and wind the label about the pasted periphery thereof. Upon leaving the label receptacle the mandrel with the picked up label will be brought into engagement with the presser or ironing member 24, and the label will be smoothly pressed upon the mandrel by the rotation of the latter, the spring arm having been released by the engagement of the mandrel with the presser member 24. The label at this point will be seen to fit snugly about the periphery of the mandrel with one end adjacent the weighted portion of the periphery of the mandrel while the opposite end will overlie a portion of the finger opening 17 in the mandrel, the mandrel being of a size larger than the cans to which the labels are to be applied, whereby a label will not go completely around the periphery of the mandrel but will leave an exposed edge which overlies the opening 17 in the mandrel to permit of the label to be stripped from the mandrel for application to the can. Upon leaving the presser or ironing member the mandrel due to its weight will be moved into position to be engaged by the spring latch 15 whereby during the travel of the mandrel with the chain lateral vibration is prevented. The travel of the chain is at such a speed and of such a duration as to permit the labels applied to the mandrels on said chains to become practically set or tempered by the time the mandrel reaches its discharge position, which as shown is at the front end of the machine and conveniently made up of the parts about to be described.

Secured to the overhanging bracket arms 2 are angle bracket members 40, the upright vertical portions thereof have slotted ways 40^a adapted for the reception of a transversely extending rod 41 extending between the respective bracket members 40 which said rod 41 has mounted thereon for rotary movement a presser roll 42 which is normally positioned adjacent the upper end of the slotted ways 40^a by reason of the pressure exerted by the spiral springs 43. An actuating member, conveniently taking a U-shaped form and constituting a treadle 44 is provided and adapted to be actuated by the foot of the operator, the vertically extending arms 44^a of the treadle being se-

cured to the opposite ends of the rod 41, as clearly shown in Fig. 3. The bracket members 40 are conveniently enlarged at 40^b and constitute bearings for opposite ends of a pair of laterally spaced rollers 45, the shaft 45^a for one of said rollers being conveniently extended at one end beyond the adjacent bracket arm 40 and having secured thereto an operating handle 46 whereby the connected roller is positively driven. The separated rollers 45 together constitute a pocket or support for a can to be labeled, which may be placed in said pocket and between the brackets 40 by the hand of the operator or otherwise.

The operation of this feature of the invention may be described as follows: One of the mandrels 14 with a label applied thereto having in the travel of the chains 12 reached a position adjacent the point of application of the labels to the can, the operator grasps the exposed edge of the label on the mandrel which overlies the opening 17 in the mandrel, and strips said label from the mandrel and applies said edge to the can which has been placed in a pocket formed by the rollers 45. The can is thereupon given a rotary movement by rotating the handle 46 which rotates one of the rollers 45, and said can in its rotary movement will continue to draw the label from the mandrel and wind the same about its periphery. It will be observed that that end of the label last leaving the mandrel will constitute the lap end of the label on the can and since said lap end has a pasted surface from end to end it will overlie the other end of the label as is obvious. At this time the operator places his foot upon the treadle actuating member 44, and by exerting downward pressure thereon will move the presser member 42 against the action of the springs 43 downwardly until said presser member firmly engages the labeled can, and when in this position the rotation of the labeled can is continued by the operator through the medium of the handle 46 and the label will thereby become firmly affixed to the can. It has been seen that prior to this application to the can the label has become properly tempered. The label upon the can will be practically devoid of further stretching and by subsequent contraction when dry it will be firmly and smoothly affixed to the can and in a manner devoid of the customary wrinkles.

While various instrumentalities may be employed in affixing the tempered labels to the cans, that shown is an exceedingly simple and economical construction and permits of a quite rapid labeling of the cans since the operator may pick up the can and position it with his right hand and while so positioning the can strip the edge of the label from the mandrel and engage the same

with the positioned can with his left hand and so soon as the label is so engaged the operator with his right hand will impart the necessary rotation to the can through 5 the medium of the actuating handle 46, and at the proper time the treadle 44 will be depressed by the foot so as to bring the presser roll into position while the rotation of the can is continued through the means 10 of the handle 46 and connected roller 45.

Having thus described the invention, what is claimed is:

1. In a can labeling machine, the combination of a pasting member, an endless traveling member having a plurality of label conforming rolls adapted in the movement of the traveling member to receive a supply of paste from the pasting member, and a label receptacle arranged in the path 20 of the conforming rolls and adapted to contain superimposed labels to be picked up by said conforming rolls.

2. In a can labeling machine, the combination of a paste applying member, a label receptacle, a presser member and a rotary member adapted to receive a supply of paste from the pasting member and to move in contact with a label in the label receptacle to pick up the same and by its rotation 30 to wind the label thereabout, said presser member being arranged in the path of the paste applying member after the application of the label thereto, and means for subsequently applying the pasted label to a can 35 or the like.

3. In a can labeling machine, the combination of a paste applying member, a label receptacle and a plurality of rotary members adapted to successively move into operative position relative to the paste applying member to receive a supply of paste from the same and to move in contact with the labels in the label receptacle to pick up the same and by their rotation to wind the labels thereabout, and 45 a common drive means for said rotary members.

4. In a can labeling machine, the combination of a paste applying member, a label receptacle and a plurality of connected rotary members adapted to receive a supply of paste from the pasting member and to move in contact with the labels in the label receptacle to pick up the same and by their rotation to wind the labels thereabout, and 55 means for applying the pasted labels to cans.

5. In a can labeling machine, the combination of a paste applying member, a label receptacle and a rotary member having a curved periphery adapted to receive a supply of paste from the pasting member and to move in contact with a label in the label receptacle to pick up the same and by its rotation to wind the label thereabout, a 60 presser member in the path of the applied

label and means spaced from the last mentioned means to apply the pasted label to a can or the like.

6. In a can labeling machine, label applying means, and means for pasting and treating the label to be applied including a rotary mandrel, a label support, and an endless carrier for the mandrel, the label applying means being located at a point remote from the label support in the direction of travel of the endless carrier, the said mandrel being adapted to pick up a label from the support, whereby in the movement of the mandrel to the label applying means the label may become tempered and conformed. 70 75

7. In a can labeling machine, can label applying means, and means for pasting and treating the label to be applied including an endless carrier having a plurality of independent rotatable label carrying members, and pasting instrumentalities operatively associated with the carrying members. 80 85

8. In a can labeling machine, can label applying means, means for pasting and treating the label to be applied including a rotary mandrel, and means carried by the mandrel for normally retaining the same from rotation. 90

9. In a can labeling machine, can label applying means, means for pasting and treating the label to be applied including a rotary mandrel and a weight for the mandrel. 95

10. In a can labeling machine, can label applying means, means for pasting and treating the label to be applied including a rotary mandrel, a weight for the mandrel, and means operatively associated with the mandrel for preventing lateral vibration of 100 105 the same.

11. In a can labeling machine, can label applying means, and means for pasting and treating the label to be applied including an endless carrier having a plurality of rotary mandrels, and pasting instrumentalities operatively associated with the mandrels. 110

12. In a can labeling machine, can label applying means, means for pasting and treating the label to be applied including an endless carrier having a plurality of rotary mandrels, and pasting instrumentalities operatively associated with the mandrels and a weight carried by each of said mandrels. 115 120

13. In a can labeling machine, can label applying means, means for pasting and treating the label to be applied including an endless carrier having a plurality of rotary mandrels, pasting instrumentalities operatively associated with the mandrels, a weight carried by each of said mandrels, and a spring arm for preventing rotation of the mandrels. 125

14. In a can labeling machine having 130

- means for applying a pasted label to a can, a label treating member comprising a mandrel having a curved periphery, means for applying paste to the mandrel, and a weight in the mandrel.
15. In a can labeling machine having means for applying a pasted label to a can, a label treating member comprising a mandrel having a curved periphery, and means for applying paste to the mandrel, an endless carrier for the mandrel, said mandrel having an opening in the periphery thereof, adapted for the insertion of label removing means at the edge of the pasted labels.
16. In a can labeling machine, the combination of a paste applying member, a label receptacle arranged at one side of the paste applying member, an endless carrying member, a plurality of label receiving members mounted on said carrier member for independent rotation, and means for imparting movement to the carrier member, whereby the label receiving members will move successively into operative relation to the paste applying member and the label receptacle.
17. In a can labeling machine, the combination of a rotary paste applying member, a label receptacle arranged at one side of the paste applying member, an endless carrying member, a plurality of label receiving members mounted on said carrier member each rotatable about its own axis, and means for imparting movement to the carrier member whereby the label receiving members will move successively into operative relation to the paste applying member, and the label receptacle, by a rotary movement to receive an application of paste and wind a label therearound.
18. In a can labeling machine, the combination of a rotary paste applying member, a label receptacle arranged at one side of the paste applying member, an endless carrying member, a plurality of rotary label receiving members mounted on said carrier member, means for imparting movement to the carrier member whereby the label receiving members will move successively into operative relation to the paste applying member and the label receptacle, and a common drive for imparting movement to the carrying member and to said paste applying member.
19. In a can labeling machine, the combination of a rotary paste applying member, a label receptacle arranged at one side to the paste applying member, an endless carrying member, a plurality of rotary label receiving members mounted on said carrier member, means for imparting movement to the carrier member whereby the label receiving members will move successively into operative relation to the paste applying member and the label receptacle, a common drive for imparting movement to the carrying member.
20. In a can labeling machine, the combination of a rotary paste applying member, a label receptacle arranged at one side to the paste applying member, an endless carrying member, a plurality of rotary receiving members mounted on said carrier member, means for imparting movement to the carrier members, whereby the label receiving members will move successively into operative relation to the paste applying member, and the label receptacle, a common drive for imparting movement to the carrying member and to said paste applying member and can label applying mechanism arranged at the discharge end of said carrying member.
21. In a can labeling machine, the combination of a rotary paste applying member, a label receptacle arranged at one side to the paste applying member, an endless carrying member, a plurality of rotary receiving members mounted on said carrier member, means for imparting movement to the carrier members, whereby the label receiving members will move successively into operative relation to the paste applying member, and the label receptacle, a common drive for imparting movement to the carrying member and to said paste applying member, the rotary paste applying member moving at an increased speed relative to the movement of the carrying member and can label applying mechanism arranged at the discharge end of said carrying member.
22. In a can labeling machine, the combination of pasting instrumentalities, labeling instrumentalities, and pressing instrumentalities, a label supporting mandrel, and means for moving said mandrel between the several instrumentalities, whereby the mandrel will receive a coating of paste from the pasting instrumentalities, subsequently picking up a label and finally ironing the same about its periphery whereby to conform the label, and can label applying mechanism.
23. In a can labeling machine, the combination of pasting instrumentalities, labeling instrumentalities and pressing instrumentalities, a traveling carrier movable relative to said instrumentalities, and a plurality of separated label carrying mandrels mounted upon the carrier.
24. In a can labeling machine, the combination of pasting instrumentalities, labeling instrumentalities and pressing instrumentalities, a traveling carrier movable relative to said instrumentalities, and a plurality of rotatable separated label carrying mandrels mounted upon the carrier.
25. In a can labeling machine, the combination of pasting instrumentalities, labeling

instrumentalities, and pressing instrumentalities, a traveling carrier movable relative to said instrumentalities, and a plurality of weighted rotatable separated label carrying 5 mandrels mounted upon the carrier.

26. In a can labeling machine, the combination of pasting instrumentalities, labeling instrumentalities, and pressing instrumentalities, a traveling carrier movable relative 10 to said instrumentalities, a plurality of rotatable separated label carrying mandrels mounted upon the carrier, and means for properly positioning the mandrels as they move successively into operative relation to 15 the several instrumentalities.

27. In a can labeling machine, the combination of pasting instrumentalities, labeling instrumentalities, and pressing instrumentalities, a traveling carrier movable relative 20 to said instrumentalities, a plurality of rotatable separated label carrying mandrels mounted upon the carrier, can label applying mechanism arranged in the path of said carrying member, at a point removed from 25 the pressing instrumentalities, and means for preventing lateral vibration of the mandrels while being moved to the can labeling appliances.

28. In a can labeling machine, an endless 30 carrying member having mounted thereon a plurality of label carrying mandrels separated one from the other, pasting means for said carrying mandrels, means for applying a label to the pasted mandrel, a rotatable can support 35 arranged adjacent to the path of the endless carrying member and lever actuated label presser means movable toward and from the supported can for affixing the label thereto.

29. In a can labeling machine, an endless 40 carrying member having mounted thereon

a plurality of independently rotatable label carrying mandrels separated one from the other, pasting means for said carrying mandrels, means for applying a label to the pasted mandrel, a rotatable can support arranged adjacent to the path of the endless carrier and lever actuated label presser means movable toward and from the supported can for affixing the label thereto. 45

30. In a can labeling machine, the combination of label pasting and tempering appliances, including a traveling conforming mandrel, in combination with a can support adjacent thereto, the latter comprising a rotatable support, and opposed spring held 50 presser roller, and actuating means for the latter.

31. In a can labeling machine, the combination of labeling instrumentalities including a can support, a paste roll arranged 60 rearwardly of the can support, a label support rearwardly of the paste roll, an endless carrier, a plurality of rotatable mandrels mounted upon the endless carrier, and means for moving said carrier whereby the mandrels in a movement away from the labeling instrumentalities will pick up paste from the paste roll, and a label from the label support, and subsequently assume a position in the return movement of the carrier 65 adjacent the labeling instrumentalities, whereby the label is tempered prior to its application to the can. 70

In testimony whereof I affix my signature in presence of two witnesses.

FREDERICK H. KNAPP.
